UNITED STATES PATENT OFFICE.

PAUL McMICHAEL, OF FLUSHING, NEW YORK, ASSIGNOR TO THE HYDROCARBON REFINING PROCESS CO., INC., OF NEW YORK, N. Y., A CORPORATION OF NEW YORK.

REFINING HYDROCARBON OILS.

Application filed May 25, 1925. Serial No. 32,565.

This invention relates to improvements in the refining of petroleum hydrocarbons, and more particularly relates to an improved method for refining light petroleum oils and distillates, especially gasoline containing cracked oils and pressure distillates. The process of the invention is particularly applicable to the treatment of cracked oils such as those resulting from the cracking 10 of certain California crude oils, the gasoline from which when obtained by the commonly used refining process employing sulphuric acid and sodium plumbite frequently becomes discolored upon standing exposed to light becoming dark yellow or even reddish 15 brown with concurrent precipitation of gummy substances. The process of the invention, however, is also useful in refining other petroleum oils, particularly light 20 cracked oils.

For many commercial purposes, gasoline is considered satisfactory if it passes certain tests as to color, corrosive properties and sulphur content. Gasoline intended for use as 25 a motor fuel is usually considered to be of satisfactory merchantable quality if in color it is equal to or better than 22 on the Saybolt universal chronometer scale (A. S. T. M. tentative method of test—serial designation D. 156-23T), if it does not discolor a strip of mechanically polished pure sheet 30 copper after being heated therewith for 3 hours at 122° F. (A. S. T. M. tentative method of test—serial designation D. 130-35 22T), and if on being shaken thoroughly with a strongly alkaline solution of sodium plumbite neither it nor the solution is discolored, and on being further shaken thoroughly with the solution after the addition 40 of flowers of sulphur neither it nor the sulphur is discolored ("Doctor Test" for Gasoline—page 605 bulletin No. 17 of the Kansas City Testing Laboratory).

Hitherto, the general practice in the refining of petroleum oils such as gasoline and gasoline containing fractions has involved treatment of the oil with sulphuric acid. The methods of acid treatment commonly employed have several disadvantages. For

example, the acid treatment as usually carried out tends to introduce sulphur into the oil in a form that is difficult to remove and makes it difficult to bring the oil to a quality where it will pass the corrosion test. Likewise in the treatment of oils containing considerable amounts of unsaturated materials, such as cracked oils, treatment with strong sulphuric acid tends substantially to denude the oil of unsaturated constituents. Unsaturated compounds such as olefines constitute an excellent and advantageous constituent for motor fuel and their removal introduces an unnecessary loss. Furthermore, difficulties in disposing of waste acid and acid sludge also are encountered.

It has frequently been observed that certain petroleum distillates, especially those obtained from the cracking distillation of certain California crude oils, tend to become discolored with relative rapidity, turning 70 yellow or even reddish brown, especially upon exposure to direct sun light, and usually with separation of gummy substances, even after these distillates have been refined according to one or another of the commonly 75 used methods that involve the use of sulphuric acid and sodium plumbite. The research leading up to this invention indicated that this tendency to form gummy substances and to discolor might be related 80 to the presence of selenium as a constituent of the oil, and the improved process of the invention provides for the substantially complete removal of any selenium present. The invention, however, is not predicated upon 85 this premise.

According to the present invention, the oil to be refined is subjected to treatment with sulphur dioxide gas and is then subjected to treatment with an absorbent material such as fuller's earth. The treatment with absorbent material advantageously follows the treatment with sulphur dioxide gas before the oil is subjected to any other treatment. Following the treatment with absorbent material, the oil may be washed with water, and the washing operation may include treatment with an alkaline solution

such as a dilute solution of sodium hydroxide or more advantageously of ammonia, to remove any traces of sulphur dioxide remaining. Following the treatment with absorbent material, the oil may be subjected to further chemical treatment, for example, it may be subjected to treatment with an alkaline hypochlorite solution or to treatment with an alkaline plumbite solution. Following the treatment with absorbent material, or following subsequent chemical treatment, the oil may be distilled.

The invention will be further described in connection with the accompanying drawings, which illustrate in a diagrammatic manner one form of apparatus adapted for carrying out the process of the invention, but it will be understood that other and different apparatus can be employed and that the invention is not limited to operations carried out in apparatus of the character illustrated.

The apparatus illustrated in the drawing comprises a treater for contacting the oil with sulphur dioxide gas and filters for filtering the oil through absorbent material after the treatment with sulphur dioxide gas. Where the oil is subjected to further chemical treatment or is redistilled following the treatment with absorbent material, the further refining operations may be carried out in any of the well known forms of apparatus.

Referring to the drawing, the oil to be treated is supplied through connection 1 and by means of pump 2 is forced through pipe 3 to the upper end of the treater 4 and after flowing downwardly therethrough is then forced through one or the other of the filters 5 and 6. The oil escapes from the lower end of the treater through pipe 7. A distributor 8 for introducing sulphur dioxide gas is arranged somewhat above the lower end of the treater, and a pump 9 is provided for forcing sulphur dioxide gas through pipe 10 and into the treater through the distributor 8. One or more screens or other distribution promoting means 11 may also be arranged above the distributor to further promote distribution of sulphur dioxide through the oil flowing downwardly through the treater. The sulphur dioxide gas rises through the oil in the treater, and the unconsumed gas escapes through pipe 12 and is recirculated through the oil by means of pump 9 together with fresh sulphur dioxide gas supplied through connection 13. A safety valve 14 is provided to prevent excessive rise of pressure in the treater and a level gage 15 is arranged for controlling the level of oil in and the flow of oil through the treater. The oil escaping from the lower end of the treater through connection 7 is forced through one of the filters by means of pump 16. Two or more filters are provided so that the operation can be carried

out in a continuous manner, one or more of the filters being used for treatment of the oil while others of the filters are being charged with absorbent material or discharged after the absorbent material is no longer active. The oil escapes from the filters through connection 17.

In operation, the treater is kept substantially full of oil to provide for maximum contact of the oil with the sulphur dioxide gas in the treater and the oil is forced through the treater at a rate sufficient to allow the necessary period of contact with the sulphur dioxide gas with concurrent regulation of the rate of circulation of the sulphur dioxide gas. Vigorous agitation is maintained in the treater by the rising gas currents and the sulphur dioxide is thus intimately contacted with the oil. The sulphur dioxide gas introduced through connection 18 may be supplied from any suitable source, for example from a burner of any of the known types in which sulphur is burned to form sulphur dioxide. Following the treatment with sulphur dioxide gas, the oil as it escapes from the treater is subjected to treatment with absorbent material. In the apparatus illustrated, this treatment is carried out by forcing the oil through a filter bed of the absorbent material. The treatment with absorbent material, however, may be carried out in other ways, for example, the oil may be agitated with a portion of the absorbent material, and the absorbent material then separated by filtration or by settling followed by filtration. Suitable absorbent materials include fuller's earth, infusorial earth, silica gel and the like. Fuller's earth is particularly advantageous. The oil as it escapes from the treater is usually discolored tending to be more or less blackish. Immediate treatment with absorbent material, in accordance with the invention, removes this discoloration and such impurities as tend to cause it. If the oil is subjected to treatment with water, as in a washing operation, after the treatment with sulphur dioxide gas and before the treatment with absorbent material, the impurities present apparently undergo some change which renders them more difficult to remove on subsequent treatment with absorbent material and the oil may retain its tendency to discolor on standing and on exposure to light. The treatment with absorbent material is accordingly best carried out before the oil is subjected to any further treatment after the treatment with sulphur dioxide gas. After treatment with the absorbent material, the oil is washed with one or more portions of water, and may also be washed with a mild alkaline solution to assist in the removal of any traces of sulphur dioxide or other acidic constituents. In some cases the oil at this stage may be of satisfactory quality, but

usually it will not meet the "doctor test" due to the presence of mercaptans or similar sulphur compounds. To remove these compounds, the oil may be subjected to further chemical treatment. For example, it may be treated with an aqueous alkaline solution of sodium hypochlorite or of calcium hypochlorite or with an aqueous alkaline solution of sodium plumbite. In conjunction with the treatment with sulphur dioxide gas, the latter is apparently somewhat more advantageous, particularly with respect to the gum content and the corrosive properties of the finished oil. If a more refined product, or an oil of better color is desired, the oil may be distilled following the chemical treatment. In the case of light oils this distillation is advantageously carried out with steam, and may be carried out in the presence of some alkaline substance such as milk of lime. As much as 98% or more by volume of the oil subjected to distillation may be taken off as distillate, but the percentage taken off as distillate will depend upon the boiling range of the oil subjected to distillation and upon the boiling range of the finished product desired.

The invention will be further illustrated by the following example, but it will be understood that this more detailed illustration is for the purpose of exemplification and that the invention is not limited thereto. A naphtha character distillate from a California crude oil was saturated with sulphur dioxide gas, was then immediately filtered through fuller's earth, and was then washed with successive portions of water until neutral. The gum content, after evaporation of 100 cc. in a hemispherical copper dish, was reduced from about 0.072 grams to about 0.021 grams, the sulphur content originally 0.123% by weight was then 0.091% by weight, and the color determined by the Saybolt universal chronometer, was 22. The oil gave an unsatisfactory "doctor test."

One part of this oil was then agitated for about 30 minutes with about 25% by volume of a 5% solution of sodium hypochlorite containing some free caustic soda and then with several successive portions of fresh water. The oil then had a satisfactory "doctor test" and showed a sulphur content of 0.0765% by weight and a gum content of 0.062 grams. This oil was then subjected to distillation with steam and about 98% by volume was taken off as distillate. The distillate so obtained gave a satisfactory "doctor test" and corrosion test, had a color of 25 and showed a sulphur content of 0.0482% by weight and a gum content of 0.022 grams.

Another part of this oil was agitated for about 30 minutes with about 5% by volume of an alkaline solution of sodium plumbite prepared by agitating a 20° Bé. solution of caustic soda with an excess of litharge and

allowing the undissolved litharge to settle out decanting the clear caustic soda solution of sodium plumbite. After agitation of the oil with the caustic soda solution of sodium plumbite the mixture was allowed to stand several hours until the lead sulphide that formed had settled out and the caustic soda solution of sodium plumbite was then drawn off together with the precipitated impurities and the oil was washed with several successive portions of water. The oil then gave a satisfactory "doctor test," had a color of 21, showed a sulphur content of 0.064% by weight, and a gum content of 0.017 grams. This oil was then subjected to distillation with steam and about 98% by volume was taken off as distillate. The distillate so obtained gave a satisfactory "doctor test" and corrosion test, had a color of 25, showed a sulphur content of 0.041% and had a gum content of 0.014 grams.

It will thus be seen that the invention provides an improved method of refining hydrocarbon oils, particularly light petroleum oils, by which they can be rendered of satisfactory merchantable quality in an efficient and effective manner and the invention has the further advantage that the oils so refined, particularly cracked oils produced from California crudes of the type above referred to, are of improved stability.

I claim:

1. An improved method of refining cracked hydrocarbon oils, which comprises subjecting the oil to treatment with sulphur dioxide gas, and thereafter before any further treatment subjecting the oil to treatment with an absorbent material. 100

2. An improved method of refining cracked hydrocarbon oils, which comprises subjecting the oil to treatment with sulphur dioxide gas, and thereafter before any further treatment subjecting the oil to treatment with fuller's earth. 105

3. An improved method of refining cracked hydrocarbon oils, which comprises subjecting the oil to treatment with sulphur dioxide gas, then subjecting the oil to treatment with an absorbent material and thereafter washing it with water. 110

4. An improved method of refining cracked hydrocarbon oils, which comprises subjecting the oil to treatment with sulphur dioxide gas, then subjecting the oil to treatment with an absorbent material and thereafter washing it with water and with an aqueous alkaline solution. 115

5. An improved method of refining cracked hydrocarbon oils, which comprises subjecting the oil to treatment with sulphur dioxide gas, then successively subjecting the oil to treatment with an absorbent material, to a water wash, and to a treatment with a refining agent for the removal of sulphur. 120

6. An improved method of refining 130

cracked hydrocarbon oils, which comprises subjecting the oil to treatment with sulphur dioxide gas, then successively subjecting the oil to treatment with an absorbent material, 5 to a water wash, and to a treatment with a refining agent for the removal of sulphur, and thereafter distilling the treated oil.

7. An improved method of refining cracked hydrocarbon oils, which comprises subjecting the oil to treatment with sulphur ¹⁰ dioxide gas and then to treatment with an absorbent material.

In testimony whereof I affix my signature.
PAUL McMICHAEL.
